UNITED STATES PATENT OFFICE.

THEODORE STOCKMARR, OF NEW YORK, N. Y.

IMPROVEMENT IN FLUTING-MACHINES.

Specification forming part of Letters Patent No. 137,258, dated March 25, 1873.

To all whom it may concern:

Be it known that I, THEODORE STOCKMARR, of the city, county, and State of New York, have invented an Improvement in the Chains of Fluting-Machines, of which the following is a specification:

In what is known as the French fluting-machines endless chains are used to effect the fluting instead of rollers. This invention relates to machines of this class; and it consists in the combination of two chains—one having T-headed links and the other round-headed links—whereby a fluting of novel character is produced, composed of approximately-circular flutes and intervening flat surfaces.

In the accompanying drawing, Figure 1 is a longitudinal section of chains constructed according to my invention, and Fig. 2 is a profile view of the fluting produced by such chains.

A and B are the two chains composing the machine. They are represented as passing round rollers C C. Links pivoted together by pins d d form the chains, those in the chain

A having round heads a a and those of the chain B having flat T-heads b b. The chains are so arranged relatively to each other that their links shall mesh or work into one another, the heads of the links of each chain intervening between those of the other chain, as represented in Fig. 2.

The fluting, as before stated, is composed of approximately-circular flutes e e and intervening flat portions f f. The circular flutes are formed by the round heads a a of the chain A, and the flat surfaces by the flat T-heads b b of the chain B.

Claim.

The combination, in a fluting-machine, of the two chains A and B, the one having round-headed links and the other having T-headed links, substantially as and for the purpose herein set forth.

TH. STOCKMARR.
